(57) **CLAIM**

The ornamental design for a pouch for holding a radio, as
shown and described.

DESCRIPTION

FIG. 1 is a perspective view of a pouch for holding a radio in
accordance with the present invention.

FIG. 2 is a front view of the pouch of FIG. 1.

FIG. 3 is a right side view of the pouch of FIG. 1.

FIG. 4 is a rear view of the pouch of FIG. 1.

FIG. 5 is a left side view of the pouch of FIG. 1.

FIG. 6 is a top view of the pouch of FIG. 1; and,
FIG. 7 is a bottom view of the pouch of FIG. 1.

Those elements shown in dashed lines are included for the
purpose of illustrating environment and form no part of the
claimed design.
